AUTOMATIC TELEPHONE SWITCH

Charles P. Smith and Geoffrey Newton, Aldwych,
London, England, assignors to International
Standard Electric Corporation, New York,
N. Y., a Corporation of Delaware

Application July 28, 1932, Serial No. 625,324,
and in Great Britain November 27, 1931

20 Claims. (Cl. 179—27.53)

This invention relates to switching mechanisms more particularly, though not exclusively, for use as non-numerical or numerical selectors in automatic or semi-automatic telephone exchange systems.

The object of the present invention is to provide a switching mechanism which is cheap and simple in operation and which gives much quicker switching operation than the switches of the general type which have been previously proposed.

The switch mechanism according to the invention is particularly adapted for use in common control or marking systems of automatic or semi-automatic telephony.

One feature of the invention comprises a switch mechanism adapted to make connection between any one of a plurality of incoming lines and any one of a plurality of outgoing lines, in which each incoming line is connected to a switching unit and each outgoing line is connected to a contact set individual to each of said incoming lines and in which control means are provided to select and move all the contact sets connected to one outgoing line to an off-normal position, and further means are provided for moving each switching unit to an off-normal position, connection being obtained between a contact set and a switching unit when both have been moved off-normal.

According to another feature of the invention the contact bank of a switch mechanism comprises a number of groups of contacts each group including a contact individual to each outgoing line, one of said groups being used for selecting purposes only, and the other groups being used for connecting purposes only.

The above and other features of the invention will be better understood from the following description of one embodiment thereof shown in the accompanying diagrammatic drawings in

40 which:

Fig. 1 is a cross-sectional plan view of the switch showing one outgoing bank multiple,

Fig. 2 is a partial view of one side of the switch mechanism,

45 Fig. 3 is a view of one end of the switch mechanism showing the main operating mechanism.

Fig. 4 is a circuit arrangement for the switch when used as a second group selector in a system having feed in the first stage.

50 The switch is rectangular in horizontal cross section, the two longer sides comprising flat contact banks on each of which each outgoing line appears five times so that each line makes ten appearances in the bank. Each line multiple is

55 formed by a bundle of 30 bare wires suitably

insulated from one another, giving sets of 10, a, b and c wires. The multiple enters from one end of the bank at which three connecting tags are provided and the wires are turned off at right angles at intervals in groups of three (a, b and c wires) as shown in Fig. 1, the tips of these wires forming the multiples as shown. In addition two test or marking wires 11, 12 connected to wiring tags 2, 3 at the terminal end of the switch pass right through the bank to commutators 28 at the opposite end of the switch. The complete bank comprises a number (250 for instance) of outgoing line multiples assembled one above the other in horizontal rows. The multiples extending to the opposite faces of the switch may be kept separate, and used for different groups of outlets if desired.

It will be appreciated that each multiple face of the switch consists of five vertical groups of sets of contacts, each set being individual to one outgoing line. Associated with each vertical group is a vertical switching unit formed by three metal angle bars 1 joined by insulating cross members 16. The switching units are pivoted top and bottom to members 20 and 36 respectively. The member 20 is the pivoted armature of an electromagnet 21 mounted on the top of the switch frame, while the member 36 forms part of a two armed lever pivoted to the bottom of the switch framework and carrying a counterweight 37 which ensures that the magnet 21 will be able to move the switching unit. It will be noted that the magnet 21 and the lever 36 are mounted in such a way that the switching unit 1, 16 associated therewith will move towards the flat contact bank but diagonally thereto as indicated by the arrow in Fig. 1. The purposes of this will be explained later. The commutators 28 are each mounted adjacent a parallel continuous conducting strip 29. Each commutator and its associated conducting strip are adapted to be wiped over by long flexible wiper members 4, 41 bridging the commutator and feeder bars. The wipers are mounted on a horizontal bar 27 fixed to slide member 25 journaled for up and down movement on a vertical guide rod 35. The member 25 carries a half-nut 26 while the guide rod 35 is mounted between two levers 31 pivoted on the spindle 34. The continuation of the spindle 34 carries the armature 32 of an electromagnet 33 which when operated tends to rotate the levers 31 against a spring 30 to engage the half-nut 26 with a screw shaft 24 which is adapted to be driven by an electric motor 5.

The ends of the bare wire multiples of each

outgoing line at each face of the bank are threaded through insulated slots in horizontal metal bars 13. These bars are normally held to the left in Figure 1 by the spring tension of the 5 multiple wires and their left hand ends are positioned for engagement with operating members 14 on the horizontal bar 27 carrying the wipers 4. Each of the switching units 1, 16 is connected to an incoming line by means of three spiral wires 10 (not shown) connected to wiring tags on the horizontal insulating bars fixed to the contact bars 1 at the top or bottom of the switch. The switch operates as follows—

The ten switching units 1, 16 constitute in effect the wipers of ten conversational switches, while the wipers 4, 4¹ constitute the test wipers of a control switch. When the switch mechanism is taken into use the motor 5 is started to rotate the screw shaft 24, and the magnet 33 is energized to bring the half-nut 26 into engagement with the shaft. The bar 27 and wipers 4 are then raised from their normal position at the bottom of the switch and test the outgoing lines by means of the commutators 28. When an idle or wanted 20 line is reached (this may be an idle line in a particular group) the electro-magnet 33 is deenergized and the half-nut 26 is withdrawn from the shaft by means of the spring 30. The bar 27 is thereby stopped opposite the ends of the bars 13 25 in which the multiple wires of the particular outlet selected are engaged, and is brought into engagement with these bars to force them to the right, Fig. 1. This action displaces the ends of the contact wires of the selected outlet to the right 30 of their normal position, in a position in which they are situated to the right of the corresponding angles 1 of the associated switching unit. One of these switching units will have been previously selected and its electro-magnet 21 is not 35 operated. The switching unit 1, 16 is now moved towards the multiple bank in a diagonal direction as previously described. The members 1 engage the corresponding wires of the displaced multiple wire and during their further movement rub 40 over the wires in a vertical and horizontal direction, at the same time further displacing said wires towards the right. The magnet 33 is then operated to withdraw the bar 27 from engagement 45 with the bars 13 so that the bars 13 and the wire multiple of the selected outlet, with the exception of the three wires engaged by the switching unit return to normal position. In addition the half-nut 26 engages the shaft 24 50 which in the meantime has been stopped and rotated in the opposite direction so that the bar 27 is returned to normal position. If the switch is used as a non-homing simple hunting switch it would remain with a pair of bars 13 pushed to the right in Fig. 1, by the horizontal bar 27 when 55 not in use. When used as a simple hunting switch of the homing type it can be arranged to home to either end of the bank as required, that is to say, if it started from the bottom it could be made after selection to home to the top and when next 60 taken into use would operate in reversed direction. Instead of having an individual motor drive for each switch, a number of switches in an exchange could be arranged for operation by means of mechanical gearing driven from a single motor. In this case a simple bevel gear drive 65 arranged for reversal could be provided.

Mechanically-operated contact assemblies are provided as required. For instance in Fig. 2 a set of contact springs 39 is shown on the magnet 21, 70 adapted to be operated by an extension of its

armature when the magnet energizes. Alternatively, a similar contact assembly could be positioned for operation by the connector bars 1 or by the lever 36. Normal springs 38 are shown at the bottom of the selector mechanism to be operated when the member 25 reaches its home position. Similar contact springs could be provided at the top of the switch.

A description will now be given of the circuit arrangement shown in Fig. 4 for the switch when used as a second group selector in a forward hold system. It is to be understood that this circuit is by way of example only, and that the switch can also be used as a call finder or a final selector or for any other suitable purpose.

On a call incoming to the switch earth is connected over wire T, contact cm1, normally closed contacts on1 of the selector (which may be for example the normal contacts indicated at 38 in Fig. 3), back contact b1, wiper pm1 and its normal contact to protected battery. A loop is extended forward on the positive and negative wires and relay A is operated over back contacts cm2, 90 cm3. Relay A operates relay B in known fashion and the motor start circuits are closed at b4 and b5. When the next digit is received magnet PM 100 of the marker switch is impaled; earth, a1, b3, winding of relay C, e1, winding of PM, battery. Relay C remains operated throughout dialling of this digit in known manner. On the first impulse the wipers of the marker switch step off 105 normal and a circuit is closed for magnet TM (which corresponds to magnet 33 of Fig. 3); earth, pm2, b2, p1, m1, g3, winding of TM, battery. Wiper 4 of the switch hunts for its marked contact as described in known manner. When this contact is reached relay M is operated; earth b7, e4, pm3, marking conductor, wiper 4, g6, winding of M, battery. When relay C falls off at the end of the digit and relay M has been 110 operated relay E pulls up; battery, winding of 115 relay E, c1, e2, m1, p1, b2, pm2, earth. The operation of relay E opens at e4 the circuit for relay M which falls back and at m1 again closes the circuit of magnet TM which hunts via wiper 4¹ 120 for an idle line in the selected group. When an idle line is found relay P operates; earth, windings of P, g5, e5, wiper 4¹ to idle battery potential on the outgoing T wire. Relay P busies the selected line by short circuiting its high resistance 125 upper winding at p2 and at p1 closes the circuit for relay H which operates and locks up over h4, b6 to earth and at contacts h1, h2 . . . connects battery to the windings of the relays CM, which correspond to the magnets 21, Fig. 2. It 130 has been assumed that the first selector stage is the battery feeding stage and earth is present on the wire H so that relay CM now operates and locks at cm4, disconnecting the positive, negative and T wires so that relays A releases followed 135 by the other relays. Switch PM then homes via its interrupter contacts, b2, pm2. The release of relay B closes a circuit for relay N over off-normal contacts on2 and b7. The operation of N maintains the field excitation of the selected 140 motor 5 at contacts n4 and reverses the direction of drive by means of contacts n2, n3. Magnet TM is energized over n1 so that the switch drives home where the contacts on2 are opened and contacts on1 closed. If no idle line has been 145 found in the selected group relay M would have re-operated on the last line via g6, wiper 4, GE lead, e4, b7, earth. With relays E and M both operated relay G energises via e2, m1, p1, b2, pm2, earth. Relay G locks via g2, e3, b6, con- 150

nects up busy tone at g_1 , operates relay N to reverse the drive at g_4 and at g_3 opens the circuit of magnet TM which is, however, operated via n_1 so that the switch homes. When the on_2 contacts open, relay N releases and releases magnet TM, the normal circuit for which is open at g_3 and also stops the motor since contacts g_7 are open. When the subscriber hangs up release takes place due to relay A releasing.

10. What we claim is:

1. A switch mechanism comprising a bank of movable contact sets arranged in a plurality of rows, a plurality of movable switching units each adapted to cooperate with the contact sets in a plurality of rows, means for moving the contact sets of a selected row into the path of said switching units and means for moving a selected switching unit to connect with a contact set in said selected row.

20. 2. A switch mechanism comprising in combination a main contact bank, an auxiliary contact bank, a plurality of switching units for cooperation with said main contact bank, a control switch unit for cooperation with said auxiliary contact bank, means for marking contacts in said auxiliary contact bank, means for driving said control switch unit over said auxiliary contact bank under control of said marking means to select a particular set of contacts in said main contact bank and means for operating one of said switching units to connect with said selected set of contacts.

30. 3. A switch mechanism adapted to make connection between any one of a plurality of incoming and outgoing lines in which each incoming line is connected to a movable switching unit and each outgoing line is connected to a contact set individual to each of said incoming lines and in which control means are provided to select and move all the contact sets connected to one outgoing line to an off-normal position and further means are provided for moving each switching unit to an off-normal position, connection being obtained between a contact set and a switching unit when both have been moved off-normal.

40. 4. A switch mechanism comprising in combination, a flat contact bank having a number of adjacent rows of contacts in which each outgoing line is connected to a number of contacts in the same row, a number of switching units each of a length sufficient to span said adjacent rows of contacts and arranged at right angles to said 50 rows and adjacent to a single set of contacts associated with each outgoing line, control means for selecting an outgoing line in said bank, further means associated with each of said contacts in a row and adapted to move all the multiple 55 contact sets of said row out of alignment with the corresponding contact sets of other outgoing lines in the remaining rows under control of said control means, and means for moving a selected one of said switching units to engage a particular 60 set of contacts in the row which has been moved out of alignment and so complete a connection between an incoming line connected to said switching unit and the outgoing line connected to said set of contacts.

70. 5. A switch mechanism as claimed in claim 4 characterized in this that said control means comprises a test wiper adapted to be moved over a commutator having a plurality of contacts each corresponding to one of said rows of contacts in 75 the switch bank and each connected to a test

wire associated with the outgoing line connected to that row of contacts.

6. A switch mechanism as claimed in claim 4 characterized in this that each outgoing line multiple comprises groups of wires in the same or substantially the same plane, said wires being arranged substantially at right angles to the face of the contact bank which is formed by the ends of said wires.

7. A switch mechanism as claimed in claim 4 characterized in this that each outgoing line multiple comprises groups of wires and that said wires forming the contacts of an outgoing line pass through slots in a bar arranged in the plane of, but at right angles to said wires, and in which a device associated with said control means is adapted to be positioned opposite the bar associated with the wires of an outgoing line and to be shifted to move said bar so that the wires are moved out of alignment with the wires of the other outgoing lines.

8. A switch mechanism as claimed in claim 4 characterized in this that the wires forming the contacts of outgoing lines pass through slots in a plurality of bars and that each switching unit 100 comprises a plurality of rigidly connected and insulated parallel contact strips, arranged to be moved bodily towards the associated portion of the contact bank in such a manner that said bars will only engage contact wires which have been 105 forced out of normal alignment.

9. A switch mechanism as claimed in claim 4, characterized in this that the wires forming the contacts of outgoing lines pass through slots in a plurality of bars and that each switching unit is 110 arranged to be moved in such a manner as to force the contact wires with which it makes contact still further out of alignment so that the switching unit when in use will not interfere with movement of said bars and contact wires and in 115 which the slots in said bars are of such length as to allow the bar to return to its unoperated position when one or more sets of wires controlled thereby are held in said last mentioned position by said switching unit.

10. A switch mechanism as claimed in claim 4 characterized in this that it comprises two oppositely disposed flat contact banks with each of which switching units cooperate.

11. A switch mechanism as claimed in claim 4, 125 characterized in this that two oppositely disposed flat contact banks are provided with each of which switching units cooperate and that for each outgoing line a plurality of sets of wires (a, b, c wires) passes along the middle of the bank, and 130 at intervals a wire of each set is turned off at right angles towards one or other flat contact bank to form the contact sets of the said outgoing line.

12. A switch mechanism as claimed in claim 4, 135 characterized in this that sets of wires for each outgoing line are multiplied and brought out to connecting tags at one end of a contact bank, and a separate test wire for each outgoing line is connected to the commutator device associated 140 with said control means at the opposite end of said bank.

13. A switch mechanism as claimed in claim 4 characterized in this that a plurality of sets of contact wires and two oppositely disposed contact banks are provided and that a slotted bar cooperates with the contact wires on each contact bank, and said control means comprises an operating bar parallel to the planes of said contact sets and adapted to cooperate with the ends of 150

both slotted bars of a selected outgoing line whereby the contacts in both banks are displaced simultaneously.

14. A switch mechanism as claimed in claim 4, characterized in this that said control means comprises a half-nut adapted to engage a screw driving shaft, and in which said half-nut is adapted to be moved out of engagement with the screw when the operating bar shifts said slotted bars to move the contact sets of a row out of alignment with the contact sets in the remaining rows.

15. A switch mechanism as claimed in claim 4, characterized in this that said control means comprises a driving shaft and that said driving shaft is driven by an electric motor individual to said shaft or by reverse drive gearing from a power shaft which may be common to a number of switches.

16. A switch mechanism as claimed in claim 4 characterized in this that said control means comprises a half nut adapted to engage a screw driving shaft and that said half-nut is carried by a slide member slidably engaging a guide rod arranged parallel to said driving shaft but movably supported on the main frame of the switch, for example on a pair of pivoted levers, in such manner that it is movable towards and away from the driving shaft so that the half-nut is engaged with and disengaged from the driving shaft, an electromagnet being associated with said guide rod to control its movement.

17. A switch mechanism as claimed in claim 4 wherein said control means comprises a half nut adapted to engage a screw driving shaft and wherein the wires forming the contacts of outgoing lines pass through slots in a plurality of

bars characterized in this that said slide member carries the operating bar for engagement with the ends of the slotted contact bars so that when the said guide bar is moved for example under the influence of a spring to bring the half-nut out of engagement with the driving shaft, the said operating bar simultaneously engages with and displaces the slotted contact bar opposite which it stands.

18. A switch mechanism as claimed in claim 4 characterized in this that each switching unit is vertically arranged and is pivotally mounted at one end on a counterweighted lever and at the other end on a lever carrying the armature of an electromagnet individual thereto and adapted when operated to shift the switching unit into engagement with the contact bank.

19. A switch mechanism as claimed in claim 4 wherein each switch unit is provided with mounting levers having pivots characterized in this that the pivots of said mounting levers are horizontal and at an angle to the plane of the flat contact bank whereby when operated the bars of the switching unit move towards the bank in an upward and diagonally forward direction so as to force the contact wires with which it makes contact still further out of alignment and to move in contact with said wires in such a way as to clean both the contact wires and the bars of the switching unit.

20. A switch mechanism as claimed in claim 4 characterized in this that the control means comprises a commutator device associated with a marking switch adapted to be set by impulses.
